UNITED STATES PATENT OFFICE

MORTON C. TALCOTT, OF HARTFORD, CONNECTICUT, ASSIGNOR TO THE BILLINGS & SPENCER COMPANY, OF HARTFORD, CONNECTICUT, A CORPORATION OF CONNECTICUT

BOARD DROP HAMMER

Application filed May 8, 1926. Serial No. 107,662.

The invention relates more particularly to board drop hammers having more than one pair of lifting rolls and hence adapted for operating extra heavy hammers. The object 5 of the invention is the simplification of the means for causing the rolls to grip and release the hammer board simultaneously and with substantially equal pressure so as to avoid temporary overload of either pair of 10 rolls which injures the hammer board.

The invention is susceptible of embodiment in various forms and is illustrated in the accompanying drawing in the form at present preferred.

15 Fig. 1 is a front elevation of a board drop hammer having the invention applied.

Fig. 2 is a larger scale elevation of the roll head.

20 Fig. 3 a section thereof, on line III—III; and

Fig. 4 is a horizontal section on line IV—IV.

The drop hammer consists, as usual, of a base 1, two uprights 2, between which the 25 hammer proper 3 is guided and lifted by the hammer board 4, and a superstructure or roll head frame 5. The several pairs of lifting rolls, two in the present case, are fixed on roll shafts 6. The front rolls are marked 30 7 and 8 and the rear rolls 7^a and 8^a respectively. The ends of the shafts 6, for the front rolls 7 and 8, are journaled in roll 35 carriages 9 mounted for rectilinear movement in the roll head frame. These roll carriages may consist of blocks of rectangular cross section, as indicated, fitted in appropriate slideways 10 in the head frame, there being one such block to support each 40 end of each roll shaft. When the hammer is being lifted, part of its weight, which may be several thousand pounds, is borne by the two lifting rolls 7 and 8 and by the latter transmitted with substantial equality to the bottoms of the upper and lower horizontal 45 slideways of the head structure and as the latter have considerable bearing surface the roll carriages 9 move freely thereon in both directions and due to the flatness of these surfaces, quite as freely in one direction as the other which is an advantage in

producing simultaneous and equal movement in that the effect of the gravity of the rolls on the roll-moving and roll-driving means is thus largely eliminated.

This advantage is obviously independent 55 of the means for imparting movement to the roll carriages. In the present case, these sliding blocks or roll carriages are each provided with a link 11 by which they are connected to the opposite ends of equalizing 60 levers 12, placed closed to the uprights of the head frame. The levers 12 are fulcrumed on the eccentric ends 13 of a sleeve 14 and the arm 15 of this sleeve is connected, directly or otherwise, to the friction bar 16 65 or to such other hammer-controlled actuating means as may be employed in the particular hammer. The eccentric sleeve 14 is journaled on a cross shaft 17 fixed in lugs projecting forwardly from the head frame as 70 indicated in Fig. 4. Vertical movement of the friction bar 16 will thus move the roll carriages 9 in their slideways toward and from the hammer board and inasmuch as the fulcrum of the yoke structure represented 75 by the two levers 12, is central between the connection of the links 11 therewith, the pressure exerted by the friction bar will be equally divided between the rolls 7 and 8.

It will be understood that the friction bar 80 is operated or controlled by the hammer 3 as customary. That is to say its lower end extends through a knock-off mechanism indicated generally by the numeral 18 and containing a knock-off bolt adapted to hold the 85 friction bar in its elevated position until engaged by the cam face 19 on the hammer, whereupon the bolt is operated to release the friction bar, allowing it to descend. This downward movement, by rocking the eccen- 90 trics 13, advances the front rolls 7 and 8 against the board, causing the hammer to be again lifted. In its upstroke the stud 20 on the hammer engages and lifts a lever 21 connected to the friction bar so as to raise the 95 latter. Such upward movement of the friction bar simultaneously withdraws both front rolls from the hammer board, so that the hammer again falls and so on.

The upper front roll 7 is driven by the 100

gearing 22 from the axle of the rear roll and the pulley 23 thereon. The lower front roll 8 is similarly driven by gearing 24 and a belt pulley 25 on the corresponding rear roll shaft.

5 The rear rolls are journaled, as customary in this art, in eccentric bushings 26, the rearwardly projecting arms of which are rigidly joined together by cross pins 27 and the cross pins of the upper and lower rolls are both connected to an adjustment rod 28, the longitudinal position of which determines the position of the rear rolls with reference to the surface of the hammer board. Below 10 the rolls the machine is provided with the usual board clamp 29 controlled by the foot treadle 30, as usual.

I claim:

20 1. In a multiple roll-set board drop hammer, the combination of upper and lower board lifting rolls, independent upper and lower carriages for the rolls of each roll-set, each such carriage having a slideway and being mounted therein for rectilinear movement toward and from the hammer board, pressure equalizing means connecting said carriages and hammer-controlled mechanism for moving said equalizing means and also said roll carriages toward the hammer board.

25 30 2. In a multiple roll-set board drop hammer, the combination of upper and lower board-lifting rolls, independent upper and lower roll carriages therefor, a yoke structure pivotally connected to said carriages, an eccentric for actuating said yoke structure and a friction bar connected to operate said eccentric.

35 40 3. In a multiple roll-set board drop hammer, the combination of the hammer board, upper and lower pairs of lifting rolls, carriage means for one roll of the upper pair, independent carriage means for one roll of a lower pair, slideways formed in the head structure for each of said carriage means, and means controlled by the hammer for moving said carriage means in said slideways, said means being adapted to press the rolls with equal pressure against the hammer board.

45 50 55 60 4. In a multiple roll-set board drop hammer, the combination of the hammer board, upper and lower pairs of lifting rolls, sliding carriage means for one roll of the upper pair, independent sliding carriage means for one roll of a lower pair, horizontal slideways for both carriage means, means engaged to said upper and lower carriage means adapted for equally pressing them in their respective slideways toward the hammer board and means independent of the board for driving said lifting rolls.

5. In a board drop hammer, a head structure comprising upper and lower substantially horizontal slideways, independent roll 65 carriages slidably mounted respectively

therein, upper and lower eccentric roll carriages rotatably mounted in said head structure, lifting rolls journaled in all said carriages and means for equally pressing said sliding carriages toward said eccentric carriages.

6. In a board drop hammer, a hammer board, upper and lower roll carriages independently mounted in the frame structure of the machine, a driven lifting roll journaled in each of said carriages, a yoke member connected to said carriages and hammer-controlled means for moving said yoke member in a direction toward and from the hammer board.

75 80 In testimony whereof, I have signed this specification.

MORTON C. TALCOTT.
